BY *Fisher & Moore* ATTYS.

UNITED STATES PATENT OFFICE.

JOHN H. BURKHOLDER, OF ASHLAND, OHIO, ASSIGNOR TO THE J. E. PORTER COMPANY, OF OTTAWA, ILLINOIS, A CORPORATION.

DOOR-HANGER.

No. 895,156.

Specification of Letters Patent.

Patented Aug. 4, 1908.

Application filed January 20, 1908. Serial No. 411,843.

To all whom it may concern:

Be it known that I, JOHN H. BURKHOLDER, a citizen of the United States, residing at Ashland, in the county of Ashland and State of Ohio, have invented certain new and useful Improvements in Door-Hangers, and do declare that the following is a full, clear, and exact description of the invention, which will enable others skilled in the art to which it appertains to make and use the same.

My invention relates to improvements in door hangers, and the invention consists in the construction and combination of parts substantially as shown and described and particularly pointed out in the claims.

In the accompanying drawings, Figure 1 is a side elevation of a single embodiment of the invention, and Fig. 2 is a cross section thereof. Fig. 3 is a detail in plan.

The invention as thus shown is adapted to be used on so-called sliding doors, D, suspended from and adapted to ride upon a rail or track C supported on arms 2 from a rail supporting bar B. The suspensory and adjusting means herein comprise a hanger H, carrying sheaves, rollers or wheels J therein, grooved to run on track or rail C and upon which the hanger and door are supported, the lower or bottom portion of said hanger being turned inwardly to bring it beneath the track and in the center of gravity. At this point connection is made with the door by novel suspensory means adapted to both vertically and laterally adjust the door, said means comprising a pintle 3 engaged in ears 4 of said hanger and forming a connection or support for hinge member 5, hung upon said pintle between said bars 4. A screw member 7 is engaged through a transverse threaded eye in said hinge member 5, and a yoke 8 and a threaded door supporting member 9 are hung on said screw 7. The said yoke is pivotally supported through its own ears by pintle 10 in a stud or projection 12 at the top of the bracket E, which bracket is fixed to the top edge and side of the door and has a transverse bar or rib 14 through which the suspensory or door supporting screw member 9 is adjustably engaged by nut 16 beneath.

Or to be more specific, yoke 8 is pivoted at one side of the hanger member E on a projection 12 on the left hand arm of said member, the free end of the yoke projecting towards the other arm and terminating about midway between said arm where it is opera-

tively connected to the hinge member having the transverse screw threaded eye by means of the transverse screw 7 rotatively mounted in the free ends of the yoke and the adjustable door supporting screw 9 whereby it is designed to effect the vertical adjustment of the yoke and consequently the door with reference to the track.

The lateral arms of yoke 8 are supported upon the respective and corresponding ends of transverse screw 7, and door supporting screw member 9 has an eye freely sleeved upon the outer end of said screw 7 next to the corresponding arm of the said yoke.

Yoke 8 holds the door in alinement and through screw 7 serves to adjust the door laterally in either direction exactly as much as may be needed in any given case, while screw support 9 serves to fix the elevation of the door. Two or more of these complete mechanisms can be employed for a door.

A rigid hanger may be used in place of the hinged hanger as shown. That is, the hanger H and hinge member 5 may be rigidly attached or integral with each other. Screw member 9 may be pivotally engaged upon yoke 8 direct instead of being sleeved upon transverse screw 7 as shown.

In the foregoing construction, I have aimed to make a durable as well as convenient device by which the door can be adjusted both vertically and laterally and also can be applied to a door without cutting and difficult fitting, as is the case with so many other adjustable door hangers now on the market. With these ends in view, I have provided a door plate E extending over the top of the door and providing means to connect the yoke 8 therewith. This yoke constitutes a brace connection between the traveler or hanger H that carries the door and said plate. The yoke also makes a reliable and substantial means to support the transverse adjusting screw and hold the same in right working relations. This screw, 7, also supports the entire weight of the door and its ends connect with the ends of the yoke as its only direct stay. It will be seen that the yoke is so applied as to provide reliable and durable means by which the door can be adjusted laterally on said screw. Sometimes the track settles out of line or level and lets the bottom of the door drag. This is when the vertical adjustment comes in play through screw 9, and the side adjustment is used.

when different thicknesses of lumber are used to make the door and when the wall of the building warps so that the door will bind. The yoke S affords a pivoted means between 5 door and hanger in these adjustments. Then the transverse screw can be turned and the door adjusted as desired.

Material advantages are obtained by the use of yoke S, all of which will probably be 10 better understood when it is noted that the said yoke is anchored to the door across its top edge through bracket or plate E, and whereby a bracing effect is provided there- 15 through to take up such strains as are im- posed upon the parts when the door or its carrier strikes the jamb or bumper in opening or closing the door.

The yoke guards against the bending or 20 breaking of screw 9, and also screw 7, and the parts to which they are attached, and this is 25 noticeably true when the door is adjusted either to its extreme lower or side limits and when the door is not plumb in line with the track and carrier. When not centrally 30 hung, the door in closing brings a twisting strain upon the hanger parts, the weakest point of which is at the ends of screws 7 and 9, but with the yoke construction referred to 35 herein, both ends of both screws are rigidly coupled up with the door, or, more properly speaking, with bracket E rigid with the door, and no matter how the door may be hung in respect to carrier H and track C, the hanger parts will be braced and safeguarded by the 40 yoke against strain from all sides and ends.

What I claim is:—

1. A door and a rail from which the door is hung, in combination with a hanger adapted to travel on said rail and suspensory and 10 adjusting mechanism comprising a member hinged on said hanger having a transverse threaded eye, a bracket on the door and a supporting member vertically adjustable on

said bracket, a screw through the eye of said hinged member having said door supporting 45 members engaged on its outer end and a yoke constituting a brace pivoted on said door bracket and engaged on the ends of said transverse screw.

2. In door hangers, a door and a bracket 50 thereon having a projection at its top ex- tending over the door, and a rail and a hanger adapted to run on said rail, and means connecting said bracket and hanger comprising a member having a transverse threaded 55 eye pivotally connected to the hanger, a yoke pivoted to the bracket, a transverse adjust- able screw connecting said yoke and eye member, and a vertically adjustable support- ing screw connecting said parts to raise or 60 lower the door.

3. In door hangers, a suspensory member and sheaves therein, a transverse adjusting screw supported by said member at its bot- 65 tom, a hinge member pivotally engaged be- tween said door and said transverse screw and having a door supporting screw mounted on one end thereof, and a bracket on said door a yoke pivoted on said bracket and constituting a brace member adjustably en- 70 gaged with said screw at its other end.

4. In door hangers, a suspensory carrier and a transverse screw having a pivotal con- 75 nection therewith, combined with a door and a vertical adjusting screw connected with the door and with a yoke pivotally engaged with the door and constituting a brace member across the top thereof and extending toward and engaged with both ends of the said trans- 80 verse screw.

In testimony whereof I sign this specifica-
tion in the presence of two witnesses.

JOHN H. BURKHOLDER.
